OTTO THIEME, OF ST. LOUIS, MISSOURI, ASSIGNOR TO MOON-HOPKINS BILLING MACHINE COMPANY, OF ST. LOUIS, MISSOURI, A CORPORATION.

MOTOR-KEY LOCK FOR CALCULATING-MACHINES.

1,029,957.

Specification of Letters Patent. Patented June 18, 1912.

Application filed August 7, 1911. Serial No. 642,887.

To all whom it may concern:

Be it known that I, OTTO THIEME, a citizen of the United States, residing at St. Louis, Missouri, have invented a certain 5 new and useful Improvement in Motor-Key Locks for Calculating-Machines, of which the following is a full, clear, and exact description, such as will enable others skilled in the art to which it appertains to make 10 and use the same, reference being had to the accompanying drawings, forming part of this specification, in which—

Figure 1 is a detailed view of my improved motor key lock for calculating machines. Fig. 2 is a front elevational view of the locking bar. Fig. 3 is a vertical sectional view of my combined adding and calculating machine showing my improvement attached thereto. Fig. 4 is a detailed view 20 showing the manner of engaging the totalizer wheels with their actuating devices. Fig. 5 is a detailed view showing the manner of operating the motor clutch by a motor key.

25 This invention relates to a new and useful improvement in motor key locks for calculating machines, the object being to prevent the depression of the motor key when the totalizers are not in proper registration with 30 their actuating devices. My improved motor key lock is shown in position on a combined adding and computing machine illustrated in French Letters Patent No. 388,719 dated January 16, 1908, being the 35 invention of Hubert Hopkins and commercially known as Moon Hopkins Billing Machine, but it is obvious that there are other types of calculating machines with which my invention could be used.

40 In the drawings: 1 indicates a motor key which is arranged upon two bell crank levers 2, only one of which however is shown in the drawings.

45 3 is a rod connecting the bell crank lever 2 with a bar 4, said bar controlling the clutch mechanism which connects the electric motor, 14, with the driving shaft of the machine. Upon the depression of the motor key 1, the bar 4 is moved forwardly, such 50 movement throwing the clutch in cooperative position whereby the motor will drive the machine one revolution. In Fig. 5 I have shown the bar 4 as coöperating with a clutch operating member 118, said member 55 being raised, upon the operation of the bar

4, out of engagement with a cam projection 109^a on a sleeve 109, whereby said sleeve is thrown into contact by means of the spring 110 with the worm gear 111 in mesh with the worm 112 on the armature shaft 113 of 60 the motor 14. This forms no part of my present invention, except as the same enters in combination with the other parts of the mechanism. The bar 4 is formed with a cam face 4^a which, upon the forward move- 65 ment of said bar incident to the depression of the motor key will engage the foot extension on a vertically movable bar 5 formed with suitable guiding slots through which screws or pins fastened to the frame of the 70 machine pass. The upper end of the bar 5 is formed with a relatively wide face having one or more notches 5^a therein, said upper edge coöperating with a pin 6 on the end of shaft 7. On this shaft 7 are arranged the 75 totalizer wheels 119 constituting the forward totalizers which are movable laterally with respect to the machine by means of an escapement mechanism not shown, but of which the escapement teeth 7^a on the shaft or 80 rod 7 form a part. A lever 8 connected to the end of the rod 7 and operated by a spring 9 tends to move the totalizer wheels and shaft 7 leftwardly when the escapement mechanism is operated by projections on the 85 laterally movable carriage of the typewriting mechanism, as fully set forth in the French patent aforesaid. I have indicated the platen of this carriage at 9 in the accompanying drawings. 90

When the typewriter carriage and its platen are moved to starting position at the extreme right, the groups of totalizer wheels 119 are also moved to the right so that the left-hand group is in operative relation to 95 the actuating racks. Then, as the carriage is spaced leftwardly the projections coöperate with the escapement mechanism of which the teeth 7^a form a part, so that the middle group of totalizer wheels are brought into 100 operative relation to the actuating devices. Finally, when the escapement mechanism is again operated, the right-hand group of totalizer wheels is brought into operative 105 relation to the actuating devices. When the carriage has been moved to its starting position in which the first or left-hand group of totalizer wheels is in operative relation to the actuating devices, the pin 6 is to the right of the head of the vertically movable 110

plate 5. If the motor key should now be operated, the parts being in proper position, the plate 5 can be raised and the machine made to perform a complete operation. If 5 the typewriter carriage is now stepped leftwardly and in such stepping movement operates the escapement mechanism so as to displace the first group of totalizer wheels and replace them by the second or middle 10 group of totalizer wheels, then the pin 6 should register with the notch 5^a and permit the operation of the motor key. Should one of the totalizer wheels 119 be displaced as sometimes may happen, so that the totalizer 15 is prevented from moving the necessary distance, it follows that the registration of any number into the totalizer wheels would be an improper registration and hence the previous registrations in the totalizer wheels 20 would be disturbed so that it would be impossible to obtain a correct total. Upon the arrest of the groups of totalizer wheels in other than correct position, the pin 6 will either not properly register with the notch 25 5^a or be located beyond the ends of the widened portion of plate 5 and hence will interfere with the operation of the motor key preventing the motor key from being depressed.

30 In order to prevent the parts from being sprung should an ignorant operator attempt to operate the motor key by force; notwithstanding the notice to him by the resistance of said key that the totalizer wheels are not 35 properly positioned, I provide a backing plate 11, which extends above the pin 6 and throughout the path of travel of said pin so that if an effort is made to operate the motor when the totalizer wheels are improperly 40 positioned, the rigidity of this backing plate will resist any undue springing of the parts. A spring 5^b is connected to the plate 5 to return it to normal position after operation.

The totalizer wheels 119 are normally ele- 45 vated above the actuating racks 100 and when an example is introduced into the machine through the key-board and the motor key operated, the actuating racks are permitted to move forward under the impelling 50 action of their springs until the arrest by the key position stops; then on the back stroke of the machine, the totalizer wheels are moved down into mesh with the racks and the restoring bar in moving the racks 55 backwardly after they are engaged with the totalizer wheels introduces the numbers set up on the key-board into the totalizer wheels all of which is fully set forth in French patent above referred to.

60 In Fig. 4, I have illustrated means for engaging the totalizer wheels 119 with the racks 100, the same comprising link 113 connected to one of the frame plates 49 in which the shaft 7 is mounted. This link 65 carries a tappet 113^a having a pin 113^b for

coöperating with a projection 116^a on a cam 116 and a projection 116^b on said cam, all of which is fully described in French patent aforesaid. The lower end of this link 113 is provided with a pin which coöperates 70 with a bell crank lever 173 and a link 174 operated by the rod 170 connected to the outer end.

In the event that the totalizer wheels are not shifted to the proper registering position with respect to the racks, it will be obvious that the non-registration of the pin 6 with the vibrating bar 5 will, in addition to preventing the motor key from throwing the clutch to operatively connect the motor 80 with the actuating devices, also prevent the engagement between the totalizer wheels and their actuating racks.

What I claim is:

1. The combination of shiftable totalizers 85 and their actuating devices, means for engaging said totalizers and said actuating devices and means for preventing the engagement between said totalizers and said actuating devices when said totalizers are in 90 other than correct position.

2. The combination of groups of totalizer wheels and single set of actuating devices therefor, means for shifting said groups of totalizer wheels into and out of operative relation to said actuating devices, means for engaging said totalizers and said actuating devices and means for preventing the engagement between said actuating devices and said totalizer wheels when said totalizer 100 wheels are in other than correct position.

3. The combination of groups of totalizer wheels actuating devices therefor, means for shifting said totalizer wheels into and out of operative relation to said actuating devices, means for operating said actuating devices and means for preventing the operation of said actuating devices when said totalizer wheels are in other than correct 105 position.

4. The combination of laterally shiftable totalizers and their actuating devices, means for engaging said totalizers and said actuating devices and means for preventing the engagement between the said totalizers and actuating devices when said totalizers are in other than correct position.

5. The combination of laterally shiftable totalizers and their actuating devices, means for operating said actuating devices and 115 means for preventing the operation of said actuating devices when said totalizers are in other than correct position.

6. The combination of groups of totalizer wheels and their actuating devices, means 125 for operating said actuating devices, means for shifting said totalizer wheels into and out of operative relation with respect to their actuating devices, means for engaging said totalizers and said actuating devices and 130

means for preventing the engagement between the actuating devices and said totalizers when the totalizers are in other than correct position, said means also preventing the actuating devices from being operated.

7. The combination with a group of totalizer wheels, actuating devices therefor, means for moving said totalizer wheels into and out of mesh with said actuating devices, and means for preventing the totalizer wheels from being moved into mesh with the actuating devices when said totalizer wheels are in other than correct position.

8. The combination of groups of totalizer wheels and their actuating devices, a motor drive for said actuating devices, means for preventing the motor from driving said actuating devices when said totalizer wheels are in other than correct position.

9. The combination of totalizer wheels, actuating devices therefor, a motor for operating said actuating devices, and means for preventing the motor from operating said actuating devices when said totalizer wheels are in other than correct position.

10. The combination of shiftable groups of totalizer wheels, actuating devices therefor, a motor for operating said actuating devices, means for shifting said groups of totalizer wheels so as to successively bring them into operative relation to said actuating devices, a motor for driving said actuating devices, and means for preventing the motor from operating said devices when said totalizer wheels are in other than correct position.

11. The combination of laterally shiftable groups of totalizer wheels and their actuating devices, a shaft on which said totalizer wheels are mounted, a projection carried by said shaft, and a vibratory notch bar coöperating with said projection whereby said projection constitutes an interference to prevent the operation of said bar when

the totalizer wheels are not in correct operative position. 45

12. The combination of laterally shiftable totalizers, a shaft on which the same are mounted, a recessed vibratory bar, a projection on the said shaft coöperating with said recessed bar whereby the bar is prevented from vibrating when the shaft is in certain position, and a motor key for vibrating said bar. 50

13. The combination of laterally shiftable groups of totalizer wheels, a shaft on which the same is mounted, a projection carried by said shaft, a notched vibratory bar coöperating with said projection, and a motor key for vibrating said bar. 60

14. The combination of laterally shiftable totalizers and the shaft on which they are mounted, of a projection on said shaft, a vibratory notched bar coöperating with said projection, and a backing bar for preventing said shaft from being sprung in the event that said notched bar engages said projection. 65

15. The combination of totalizers and their actuating devices, of a motor for operating said actuating devices, a clutch interposed between said motor and said actuating devices, a key for throwing said clutch into operative position whereby said actuating devices are driven by said motor, and means operated by said key and coöperating with said totalizers whereby when said totalizers are in other than proper position, said motor key is prevented from being operated. 70 75 80

In testimony whereof I hereunto affix my signature in the presence of two witnesses, this 5th day of August, 1911.

OTTO THIEME.
